UNITED STATES PATENT OFFICE.

HERBERT JOSEPH HARWOOD, OF LITTLETON, MASSACHUSETTS.

DESIGN FOR A CHAIR-BACK.

SPECIFICATION forming part of Design No. 20,818, dated June 9, 1891.

Application filed April 22, 1891. Serial No. 390,046. Term of patent 14 years.

To all whom it may concern:

Be it known that I, HERBERT JOSEPH HARWOOD, a citizen of the United States of America, residing at Littleton, in the county of Middlesex and State of Massachusetts, have 5 invented and produced a new and original Design for Chair-Backs; and I do declare, the following to be a full, clear, and exact description of the same, reference being had to the accompanying drawings, forming a part thereof.

Figure 1 represents a perspective view of a chair, showing the design for the chair-back. Fig. 2 is a side view.

15 The leading feature of the design consists in a substantially straight body to the back, and having sides flaring or diverging at the tops to top of the back, rolling over backward, and the back concavo-convex in cross-section 20 at the top.

In the representation, the letter A is the design for the chair-back. It has the body portion *a* substantially with straight sides. At the tops these sides diverge or flare outwardly, as at *a'*, the extreme top *B* of the 25 back being wider than the body *a*. This top *B* also rolls over slightly to the rear, as at *C*. The back above the body portion *a* is concavo-convex in cross-section, the concave being on the inside, as shown. 30

What I claim is—

The design for a chair-back, as described and shown.

In testimony whereof I affix my signature in presence of two witnesses.

HERBERT JOSEPH HARWOOD.
